[57] CLAIM

The ornamental design for a control device for medical treatment, substantially as shown and described.

DESCRIPTION

FIG. 1 is a top perspective view of a control device for medical treatment, showing out new design;

FIG. 2 is a front view thereof;

FIG. 3 is a rear view thereof;

FIG. 4 is a left side elevational view thereof;

FIG. 5 is a right side elevational view thereof;

FIG. 6 is a top plan view thereof; and

FIG. 7 is a bottom plan view thereof.

FIG. 1

FIG. 2

FIG. 3

FIG. 5

FIG. 4

FIG. 6

FIG. 7

UNITED STATES PATENT AND TRADEMARK OFFICE
CERTIFICATE OF CORRECTION

PATENT NO. : D296, 821
DATED : July 19, 1988
INVENTOR(S) : Lundgren, et al

Page 1 of 6

It is certified that error appears in the above-identified patent and that said Letters Patent is hereby corrected as shown below:

In the DESCRIPTION, line 2, "out" should read --our--.

In the Figures, Figs. 1, 2, 3, 4, 5 and 7 should be replaced by the enclosed Figures.

Signed and Sealed this
Fourteenth Day of March, 1989

Attest:

DONALD J. QUIGG
